US00D809031S

(12) **United States Design Patent** (10) **Patent No.:** **US D809,031 S**
Burton (45) **Date of Patent:** ** *Jan. 30, 2018

(54) **CUTTING TOOL**

(71) Applicant: **US SYNTHETIC CORPORATION**,
Orem, UT (US)

(72) Inventor: **Regan Leland Burton**, Saratoga
Springs, UT (US)

(73) Assignee: **US SYNTHETIC CORPORATION**,
Orem, UT (US)

(*) Notice: This patent is subject to a terminal disclaimer.

(**) Term: **15 Years**

(21) Appl. No.: **29/555,279**

(22) Filed: **Feb. 19, 2016**

Related U.S. Application Data

(63) Continuation of application No. 14/273,360, filed on
May 8, 2014, now Pat. No. 9,434,091.

(57) **CLAIM**

The ornamental design for a cutting tool, as shown and described.

DESCRIPTION

FIG. 1 is a front, perspective view of a cutting tool;
FIG. 2 is a front elevational view of the cutting tool shown
in FIG. 1;

FIG. 3 is a back elevational view of the cutting tool shown
in FIG. 1;

FIG. 4 is a side elevational view of the cutting tool shown
in FIG. 1, with the other side elevational view being iden-
tical;

FIG. 5 is a top plan view of the cutting tool shown in FIG.
1; and,

FIG. 6 is a bottom plan view of the cutting tool shown in
FIG. 1.

The broken lines in the drawings depict unclaimed environ-
mental subject matter.

1 Claim, 4 Drawing Sheets
